(57) **CLAIM**

The ornamental design for a water filtration device, as shown and described.

DESCRIPTION

FIG. 1 is a front, top perspective view of a water filtration device, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines show portions of the water filtration device, that form no part of the claimed design.

The dashed lines in the figures illustrate portions of the water filtration device, that form no part of the claimed design.
